GAUGE HANDLE

Joseph E. Fuhr, Elkins Park, Pa.

Application November 25, 1942, Serial No. 466,930

10 Claims. (Cl. 33—178)

The present invention relates to gauge handles and more particularly to a handle for use with taper lock plug gauges.

Handles of the taper lock type now in use are relatively expensive to manufacture by reason of the operations necessary, since each is formed from bar stock which must be cut to size, bored lengthwise, and reamed or otherwise machined to provide the tapered hole for the reception of the shank of the plug gauge. Also, drift holes or slots have to be drilled or broached in order that the gauge plugs can be ejected or released by the use of a drift pin. Furthermore, each handle so formed of bar stock is heavier than required to efficiently carry out the function of holding and supporting the gauge section in use.

Some of the objects of the present invention are: to provide an improved handle for taper lock plug gauges; to provide such a handle that is cheap and easy to manufacture; to provide a handle for taper lock plug gauges which reduces the manufacturing processes to a minimum; to provide a handle wherein the usual boring and drilling operations now necessary in making bar stock handles are eliminated; to provide a handle which is approximately one sixth as heavy as a handle made from bar stock; to provide a handle which is efficient in operation and maintains the required sensitiveness for gauging operations; and to provide other improvements as will hereinafter appear.

In the accompanying drawing, Fig. 1 represents a side elevation of a handle for a plug gauge embodying one form of the present invention; and showing in dotted lines a plug gauge in operative position; Fig. 2 represents an end elevation of the handle; Fig. 3 represents a section on line 3—3 of Fig. 1; and Fig. 4 represents a perspective of the parts in position for assembling.

Referring to the drawing, one form of the present invention consists of a handle 10 for supporting and properly manipulating a plug gauge 11 of the taper lock type. In accordance with the invention the body of the handle 10 is formed by two elongated plates 12 and 13, preferably of equal length and each of which is stamped or otherwise formed from relatively thin sheet metal, such as steel, in order to provide a rugged, rigid member suitable for the requirements of use. The plate 12 has a generally rectangular body portion terminating at opposite ends respectively in pairs of prongs 14. These prongs 14 are formed during the preferred one-operation stamping and the member thus appears as a relatively narrow

10 elongated plate having bifurcated ends with end recesses 15. The plate 13 is preferably a counterpart of the plate 12 and is formed in the same manner, and hence has end bifurcations forming 15 respectively pairs of prongs 16 with end recesses 17 bounded respectively by the pairs of prongs. The depth of the several recesses 15 and 17 is such as will allow the shank 18 of the plug gauge 11 to enter and properly locate the gauging-section of the plug for accurate use.

15 In order to bring the recesses 15 into register respectively with the recesses 17 to form two shank receiving sockets, the plate 12 has a slot 21 opening into one recess 15 at one end and extending lengthwise of the plate 12 a distance necessary for the contemplated interlocking of the two plates as will be explained. The plate 13 is also formed with a slot 22 opening into one recess 17 and extending lengthwise of the plate 13 a distance corresponding to that of the slot 21. 20 Laterally considered, the slots 21 and 22 are equidistant from the sides of the plates and hence the two plates can be fitted together in an approximately telescopic relation with each slot straddling a portion of the body of the other plate. Both slots 21 and 22 are of uniform width and each so closely approximates the thickness of the plate to be engaged as to make a snug friction fit. 25 Thus, when the two plates are brought end to end and then forced together, a handle of cruciform cross-section is formed while the pairs of intersecting recesses 15 and 17 are in register as circumferentially considered and thus provide the end sockets referred to.

30 For the purpose of providing the desired taper lock of the shank 18, the opposed faces 23 bounding each recess 15 are inwardly tapered at an angle complementary to the tapered wall of the plug shank 18. Also, the opposed faces 24 bounding each recess 17 are inwardly tapered at an angle complementary to the tapered wall of the plug shank 18. Hence, each complete skeleton-like socket is accurately dimensioned and shaped 35 to provide a friction lock for the gauge shank 18 when the two parts, namely, the handle 10 and the plug gauge shank 18, are pressed together.

35 As a means to prevent outward deflection of the pairs of prongs 14 and 16, when a plug shank enters a socket, two ferrules 25 and 26 are provided, one for each end of the handle and dimensioned to have an internal diameter to fit snugly and tightly about the outer edge faces of the aforesaid prongs. In order to maintain 40 a uniform width to the handle throughout its

length, each outer edge of the prongs 14 and 16 is cut away as at 30 to a depth equal to the thickness of the ferrule wall, and to a length substantially that of the ferrule. The end of each ferrule terminates in an annular flange 27 which forms a hole 28 having a diameter less than the distance between the outer edges of each prong pair but greater than the distance between the inner edges of the same prong pair. Thus, the two flanges 27 serve to protect the ends of the prongs from damage in use, while permitting the free entry of the gauge plug shank. It should be noted that the length of each ferrule is less than the depth of the socket about which it fits in order to laterally expose that portion of the socket which is beyond the end of the gauge plug shank when the latter is taper locked in its socket. In this way it is possible to insert a drift pin or other implement laterally of the socket to eject the gauge whenever necessary. It should also be noted that the ferrules serve the important function of restricting any outward spreading of the prongs in use and thus ensure a solid grip on the shank regardless of how many times a plug gauge is put in or taken out of the handle. In other words, there is no chance for shake or "wink" to interfere with the sensitive feel so necessary in gauges of this type. Thus, when the handle is assembled with a gauge, the taper lock possesses the rigidity of a solid gauge.

It will now be apparent that a novel gauge handle has been devised wherein material has been reduced to a minimum without detriment to the efficiency of such a handle. While relatively light in weight it has all the rigidity required for sensitive work. It is inexpensive to manufacture since it requires about one sixth the material now used in the standard gauges made from bar stock. Furthermore, the double ended construction permits the simultaneous mounting of both "go" and "no go" gauges. Also, it should be noted that the cruciform construction provides eight separate surfaces, any one or all of which can be used for indicia denoting gauge size or other informative data.

The low cost of manufacture is apparent since the plates 12 and 13 are made by stampings by the use of accurately designed dies. While the ferrules 25 and 26 serve to prevent spreading of the prongs, another important function is to maintain the handle plates positively locked at all times.

While only a single form is shown in which this invention may be embodied, it is to be understood that the invention is not limited to any specific construction, but might be applied to various forms without departing from the spirit of the invention or the scope of the appended claims.

Having thus described my invention, I claim:

1. As a new article of manufacture, a removable gauge handle of cruciform transverse section throughout its length having a tapered shank receiving socket at one end.
2. As a new article of manufacture, a removable gauge handle of cruciform transverse section throughout its length having tapered shank receiving sockets respectively at the ends thereof.

3. As a new article of manufacture a gauge handle of cruciform transverse section throughout its length having prongs at one end forming a shank receiving socket, and a ferrule encircling said prongs.

4. As a new article of manufacture a gauge handle of cruciform transverse section throughout its length having prongs at one end forming a tapered shank receiving socket, and a ferrule encircling said prongs.

5. A handle for taper lock plug gauges, consisting of two plates extending radially from a common axis, and prongs extending from one end of said plates to form together a shank receiving socket, the socket bounding edges of said prongs being tapered complementally to the tapered shank of a plug gauge.

6. A handle for taper lock plug gauges consisting of two plates extending radially from a common axis, and two sets of prongs extending respectively from the ends of said plates to form respectively two shank receiving sockets, the socket bounding edges of the prongs of each socket being tapered complementally to the tapered shank of a plug gauge.

7. A handle for taper lock plug gauges, consisting of two plates extending radially from a common axis, prongs extending from one end of said plates to form together a shank receiving socket, the socket bounding edges of said prongs being tapered complementally to the tapered shank of a plug gauge, and means to prevent spreading of said prongs when a shank enters said socket.

8. A handle for taper lock plug gauges, consisting of two plates extending radially from a common axis, prongs extending from one end of said plates to form together a shank receiving socket, the socket bounding edges of said prongs being tapered complementally to the tapered shank of a plug gauge, and a ferrule fitted about said prongs to prevent spreading when a shank enters said socket.

9. A handle for taper lock plug gauges, consisting of two plates complementally slotted for telescopic assembly with the respective plate planes radiating from a common axis, each plate terminating at opposite ends in a pair of prongs, the pairs of prongs of one plate being respectively adjacent the pairs of prongs of the other plate to form two tapered gauge shank receiving sockets, and ferrules respectively fitted about the prong pairs to prevent spreading thereof.

10. A handle for taper lock plug gauges, consisting of two plates complementally slotted for telescopic assembly with the respective plate planes radiating from a common axis, each plate terminating at opposite ends in a pair of prongs, the pairs of prongs of one plate being respectively adjacent the pairs of prongs of the other plate to form two tapered gauge shank receiving sockets, ferrules respectively fitted about the prong pairs to prevent spreading thereof, and an annular flange on each ferrule to abut the ends of the adjacent prongs without obstructing the mouth of the adjacent socket.
